UNITED STATES PATENT OFFICE.

ALVIN J. GERHARDT, OF FLINT, MICHIGAN.

FIRE-KINDLER.

1,308,009.

Specification of Letters Patent. Patented June 24, 1919.

Application filed June 8, 1918. Serial No. 238,925.

To all whom it may concern:

Be it known that I, ALVIN J. GERHARDT, a citizen of the United States, residing at Flint, in the county of Genesee and State 5 of Michigan, have invented certain new and useful Improvements in Fire-Kindlers; and I do hereby declare the following to be a full, clear, and exact description of the invention, such as will enable others skilled in the art 10 to which it appertains to make and use the same.

The object of the invention is to provide a simple and relatively inexpensive fire kindler to take the place of kindling wood, not 15 only as a means of conserving the supply of wood, but also as a convenient means for the starting of fires of soft or hard coal by furnishing the necessary heat to ignite the coal while supporting the latter in the most ef- 20 ficient position to receive the heat and to be exposed to the flame produced by the kindler, the construction of the latter being such as to be entirely consumed in the course of starting the fire.

25 Further objects and advantages will appear in the course of the following description, it being understood that changes in form and proportion may be resorted to within the scope of the appended claims 30 without departing from the spirit of the invention.

In the drawings:

Figure 1 is a plan view of a kindler constructed in accordance with the invention.

35 Fig. 2 is an end view of the same.

Fig. 3 is a side view.

Fig. 4 is a longitudinal sectional view on the plane indicated by the line 4—4 of Fig. 1.

Fig. 5 is a transverse sectional view on 40 the plane indicated by the line 5—5 of Fig. 1.

Fig. 6 is a detail view in perspective of a portion of the combustible wicking.

Fig. 7 is a plan view of a modified construction of the kindler showing a different arrangement and construction of the wicking and also a modified means for securing the same in place in the frame.

50 Figs. 8 and 9 are respectively longitudinal and transverse sections of the form shown in Fig. 7.

In the illustrated embodiment of the invention, the kindler consists of a frame or holder 10 constructed in the form of a grate 55 consisting of transverse elements 11 and longitudinal elements 12, disposed respec-

tively in parallel relations and adapted when said grate occupies a horizontal position in the fire box of a stove or furnace to constitute a proper support for the coal which 60 may be spread evenly over the upper surface thereof to a greater or less depth as may be desired, in position to be exposed to the flame rising from the combustible wicking 13 which is housed in and held by said frame. 65 The grate is of combustible material, such as light splint wood or preferably cardboard or the equivalent thereof and which is relatively inexpensive. The elements transverse and longitudinal constituting the grate are 70 locked together by kerfing one intersecting member as shown at 14 in Fig. 5 to receive the other member, very much in the same manner as the elements of egg cells are connected, so that the elements are held in their 75 proper relative positions until ready for use, and so that a number of the articles may be boxed or crated in bulk for shipment. The lower edges of the transverse members, for example, may be utilized as the base upon 80 which the structure rests upon the grate of the fire box of a stove or furnace and by constructing the longitudinal members 12 of a less depth than the transverse members as shown in Figs. 2 and 4, the flexible wicking 85 13 may be housed within the contour of the grate as indicated in Figs. 3 and 4 where it is held by a longitudinal retaining member 14 terminally secured as at 15 to the marginal transverse elements of the grate. Also 90 the intermediate transverse element 11 may be notched as shown at 17 to provide for the proper nesting of the intermediate portions of said wicking.

The wicking may consist of a filler of suitable inflammable material incased in a wrapping of flexible material, such as paper or the equivalent thereof, and in practice it has been found that a suitable inflammable mixture may be composed of sawdust one quart, 95 kerosene one gill, coal dust or finely powdered coal one quart, and melted tar, one gill. The sawdust and kerosene should be thoroughly mixed and incorporated and subsequently the coal dust and melted tar should be added 100 and the combination thoroughly stirred to secure a homogeneous and thorough distribution of the elements after which the same may be wrapped or rolled in the envelop or sheath and coiled or wrapped within the 110 seat provided therefor in the grate as shown in Fig. 1.

As above noted, the article should be placed in a horizontal position in the fire box of a stove or furnace with the unobstructed edges of the longitudinal and transverse members uppermost to form a support for the coal which should be distributed thereon before igniting the terminals of the wicking which are exposed as shown at 13^a for that purpose. The flame from the burning mixture in the wicking passes up through the grate bars or elements and immediately attacks the coal supported thereby, and in the course of the operation the grate is consumed so that there is nothing other than the ash for subsequent removal, and the use of wood in starting a coal fire may thereby be entirely avoided.

In the modified construction of device indicated in Figs. 7 to 9, inclusive, the intermediate portion of the central longitudinal element of the frame is cut away or omitted to allow more space for the arrangement of the wicking which is preferably formed in sections 18 and 19, of which the former is coiled relatively closely at the center of the frame while the latter forms an encircling or marginal element to more evenly distribute the heat in the burning of said wicking, and thereby insure the proper ignition of the coal or other fuel which is disposed upon the grate formed by the frame.

In the modified construction also the wicking is preferably held in place by means of a webbing 20 of stout paper or other inflammable material which substantially covers the bottom of the frame and therefore supports the wicking elements throughout their lengths.

It will be obvious, moreover, that the device described may be constructed at a relatively small cost and may be conveniently and compactly stored and shipped in condition for use.

Having described the invention, I claim:

1. A fire kindler having a combustible grate consisting of longitudinal and transverse intersecting elements of which the upper edges of the longitudinal elements are arranged in a common plane to form a support for fuel, and of which the intermediate portions below the fuel supporting edge

are cut away to form a housing, and an inflammable wicking arranged in the housing formed by said members or elements of the grate and disposed and secured within the 55 contour of the latter.

2. A fire kindler having a grate consisting of longitudinal and transverse intersecting combustible elements of which intermediate portions are cut away below the upper fuel supporting edges thereof to provide a housing, an inflammable wicking consisting of a combustible wrapper provided with a filling of inflammable material arranged in said housing within the contour of the 65 grate, and a retaining member connecting terminal elements of the grate for holding said wicking in place.

3. A fire kindler having a grate consisting of longitudinal and transverse intersecting combustible elements of which intermediate portions are cut away below the upper fuel supporting edges thereof to provide a housing, an inflammable wicking consisting of a combustible wrapper provided with a filling of inflammable material arranged in said housing within the contour of the 75 grate, and a retaining member consisting of an inflammable webbing secured to the lower edges of the grate members and 80 supporting said wicking in its housed relation therewith.

4. A fire kindler having a grate consisting of longitudinal and transverse intersecting combustible elements of which intermediate portions are cut away below the upper fuel supporting edges thereof to provide a housing, an inflammable wicking consisting of inner and outer elements of which the former is coiled closely and the latter is 90 arranged in encircling relation thereto, said wicking elements being arranged in the housing within the contour of the grate, and retaining means closing the bottom of the 95 grate for maintaining the wicking in position therein.

In testimony whereof I affix my signature in presence of two witnesses.

ALVIN J. GERHARDT.
